CIRCUIT ARRANGEMENT COMPRISING A
CATHODE-RAY TUBE

Zeger van Gelder and Adrianus Johannes Wilhelmus Marie van Overbeek, Eindhoven, Netherlands, assignors to Hartford National Bank and Trust Company, Hartford, Conn., as trustee

Application February 11, 1949, Serial No. 75,916
In the Netherlands March 16, 1948

4 Claims. (Cl. 315—21)

1

The invention relates to a circuit-arrangement including a cathode-ray tube comprising means for deflecting the cathode-ray beam, said tube containing a group of collecting electrodes and a further collecting electrode which is formed in such manner and arranged relatively to the group of collecting electrodes so that the cathode-ray beam during its deflection strikes alternatively a part of the further collecting electrode and the successive collecting electrodes of the group.

In various circuit-arrangements, for example in time-division multiplex telephony, use is made of cathode-ray tubes comprising a group of collecting electrodes each of which may be provided with its own output circuit. If the cathode-ray beam scans these collecting electrodes with a constant angular speed in succession, different connections are established. This has a limitation in that between the scanning of two collecting electrodes some period of time elapses uselessly. In order to reduce this period, the distance between these collecting electrodes may be made smaller but this entails the necessity of using a beam of small section so that the current strength of the beam is relatively low.

If the cathode-ray tube comprises, in known manner, the above further collecting electrode, which consequently is struck by the beam every time between the scanning of each pair of successive collecting electrodes of the group, the circuit-arrangement according to the invention permits of obviating the above disadvantages.

The circuit-arrangement according to the invention exhibits the feature that the deflecting means are coupled to the further collecting electrode in such manner that, owing to this coupling, at a deflection of the cathode-ray beam effected per se with the use of the deflecting means with substantially constant angular speed the angular speed of the beam during impingement on the further collecting electrode differs from the angular speed of the beam during impingement on the collecting electrodes of the group.

Starting with a deflection voltage or current which imparts a constant or substantially constant angular speed to the cathode-ray beam, the coupling between the deflecting means and the further collecting electrode consequently ensures that the angular speed of the beam during impingement on a collecting electrode of the system differs from that speed during impingement on the further collecting electrode.

In order that the invention may be more clearly understood and readily carried into effect, it will now be described more fully with reference to the accompanying drawing in which

2

Fig. 1 shows an embodiment of the circuit-arrangement according to the invention, the operation of which will be set out with reference to Fig. 2 and

5 Fig. 3 shows an alternative embodiment of the circuit-arrangement according to the invention. The cathode-ray tube 1 in Fig. 1, which comprises means for producing a cathode-ray beam 2 (shown diagrammatically) contains deflecting plates 3 and 4. The tube furthermore comprises a group of collecting electrodes of which four, numbered 5 to 8, are shown. These electrodes, each of which is provided with its own output circuit, have arranged behind them a further collecting electrode 9, which is connected by way of a resistance 10 to a voltage source. The left-hand deflecting plate 3 is connected through a resistance 11 to the positive terminal 12 of a battery the other end of which is earthed. In 15 the present case the terminal voltage of this battery is chosen to be such, for example, that the beam precisely strikes the left-hand collecting electrode 5 of the group if the right-hand deflecting plate 4 has earth potential. If the right-hand deflecting plate has applied to it through a resistance 13 a sawtooth voltage produced by a generator 14, the beam will move to the right with a substantially constant angular speed during the time the sawtooth voltage increases linearly or 20 substantially linearly. The beam consequently moves away from the electrode 5, passes through the first aperture 15 on to the further collecting electrode 9, then strikes the next following collecting electrode 6 of the group, subsequently 25 again impinges on the collecting electrode 9, and so forth.

If the time during which the beam strikes one of the collecting electrodes 5 to 8 is used, for example, for communication purposes, the time 30 during which the beam falls between the collecting electrodes is to be looked upon as a loss.

In order to reduce this loss of time, the further electrode 9 is coupled by way of a condenser 16 to the deflecting plate 3.

45 When in these circumstances the beam moves from the collecting electrode 5 to the collecting electrode 6, the voltage drop occurring across resistance 10 in the supply conductor of the further collecting electrode 9 will be passed on to the deflecting plate 3. This voltage drop across the plate 3 shows itself in the total effective deflecting voltage as a voltage increase with the result that the rate at which the beam is displaced is increased.

50 If the beam then strikes the collecting electrode 6 the position of the beam will again be

substantially determined by the deflecting voltage produced by the generator 14.

In Fig. 2 the deflection angle α of the beam, measured from the left-hand side of the electrode 5 in Fig. 1, is plotted as a function of the time t .

The positions of the electrodes 5 to 8 corresponding to definite deflection intervals are plotted in Fig. 2 along the ordinate in thick lines. The deflecting voltage produced by the generator 14, which increases substantially linearly and consequently corresponds to a substantially linear relationship between the deflection α and the time t , is indicated by a straight line 17.

If there is no coupling between the further collecting electrode 9 and the deflecting plate 3 and if the extension of the collecting electrodes 5 to 8 in the direction of deflection is, for example equal to that of the intermediate spaces, the cathode-ray beam moves from $t=0$ to $t=t_1$ over the electrode 5, then for an equal period of time from $t=t_1$ to $t=t_2$ over the intermediate space 15, and so forth.

However, if the coupling is made with the use of condenser 16, the angle α increases linearly with time during the impingement on the collecting electrode, that is to say during the period from $t=t_0$ to $t=t_1$ but the voltage across the deflecting plate 3 is decreased during the impingement on the further collecting electrode 9 and thus the total effective deflecting voltage is increased, as indicated by the curved part 18 in Fig. 2. Thus, the beam does not strike the collecting electrode 6 at an instant t_2 , as would be the case if the coupling were not provided, but at a prior instant t_5 and then during impingement on the electrode 6 moves again with a substantially constant angular speed. The ineffective period from t_1 to t_2 is thus materially restricted and reduced to the period from t_1 to t_5 .

It should be noted here that the variation of the deflecting voltage as a function of time, after a subsequent electrode is struck, for example the form of the part 18a of the curve in Fig. 2, depends on the time constant of the deflecting system together with the condenser 16 and a capacity 16a that may be connected in parallel with the resistance 11 and, for example, is slightly variable by varying or providing capacity 16a.

Obviously the substantially linear deflecting voltage is not necessarily supplied directly by the generator 14. This generator may, for example, supply a positive voltage pulse so that the beam is displaced substantially instantaneously to the right-hand side of Fig. 1. Owing to the time constant of the deflecting circuit the deflecting voltage prevailing between the deflecting plates decreases exponentially after the cessation of the pulse and the beam thus moves to the left. During this movement the beam is accelerated in a corresponding manner each time it strikes the collecting electrode 9.

Fig. 3 shows a variant of the circuit-arrangement shown in Fig. 1, which only differs in that the further collecting electrode 19 is arranged in front of the group of collecting electrodes 20, 21 and 22 and exhibits suitably chosen apertures 23, 24 and so forth to allow the passage of the cathode beam.

It should furthermore be noted that if it is desirable that the beam should move rapidly over the group of collecting electrodes and slowly during the intervals, this may be achieved, for example, by connecting in Fig. 1, the further collect-

ing electrode 9 to the deflecting electrode 4 instead of connecting it to the deflecting electrode 3.

As an alternative, a similar effect may be achieved by realizing the further collecting electrode 9 or 19 of the circuit-arrangement shown in Fig. 1 or 3 respectively as a secondary emission electrode. Owing to the resulting secondary emission of electrons, with a secondary emission factor $\delta > 1$, the voltage across the supply resistance 10 or 25 respectively will increase during impingement of the beam on this electrode. This increase in voltage is passed on to the deflecting plate and shows itself as a decrease of the total effective deflecting voltage with the result that the speed of the beam is reduced.

What we claim is:

1. An electrical circuit arrangement, comprising a discharge tube having a source of an electron beam, a plurality of collecting electrodes spaced apart and spaced from said source, means to deflect said beam and an electrode member having conductive portions arranged in the path of said beam between the spacings of said collecting electrodes, means to apply a signal of given phase to said deflecting means to deflect said beam in a given direction and with a given velocity thereby to cause said beam to impinge successively on said collecting electrodes and said conductive portions, and means to accelerate the deflection of said beam between adjacent of said collecting electrodes comprising an impedance element intercoupling said electrode member and said deflecting means and applying an auxiliary signal voltage to said deflecting means in the same phase as said given phase.

2. An electrical circuit arrangement, comprising a discharge tube having a source of an electron beam, a plurality of collecting electrodes spaced apart and spaced from said source, a pair of deflecting electrodes arranged to deflect said beam and an electrode member having conductive portions arranged in the path of said beam between the spacing of said collecting electrodes, means to apply a signal of given phase to said deflecting electrodes to deflect said beam in a given direction and with a given velocity thereby to cause said beam to impinge successively on said collecting electrodes and said conductive portions, and means to accelerate the deflection of said beam between adjacent of said collecting electrodes comprising an impedance element intercoupling said electrode member and one of said deflecting electrodes and applying an auxiliary signal voltage to said one deflecting electrode in the same phase as said given phase.

3. An electrical circuit arrangement, comprising a discharge tube having a source of an electron beam, a plurality of collecting electrodes spaced apart and spaced from said source, a pair of deflecting electrodes arranged to deflect said beam and an electrode member having conductive portions arranged in the path of said beam between the spacing of said collecting electrodes, means to apply a signal voltage varying substantially linearly with time and having a given phase to said deflecting electrodes to deflect said beam in a given direction and with a given velocity thereby to cause said beam to impinge successively on said collecting electrode and said conductive portions, and means to accelerate the deflection of said beam between adjacent of said collecting electrodes comprising a capacitive element intercoupling said electrode member and one of said deflecting electrodes and applying an

auxiliary signal voltage to said one deflecting electrode in the same phase as said given phase.

4. An electrical circuit arrangement, comprising a discharge tube having a source of an electron beam, a plurality of collecting electrodes spaced apart and spaced from said source, means to deflect said beam and an electrode member having conductive portions comprising secondary electron emissive surfaces arranged in the path of said beam between the spacing of said collecting electrodes, means to apply a signal of given phase to said deflecting means to deflect said beam in a given direction and with a given velocity thereby to cause said beam to impinge successively on said collecting electrodes and said conductive portions, and means to accelerate the deflection of said beam between adjacent of said collecting electrodes comprising an impedance

element intercoupling said electrode member and said deflecting means and applying an auxiliary signal voltage to said deflecting means in the same phase as said given phase.
